(57) **CLAIM**

The ornamental design for oral motor chew tool, as shown and described.

DESCRIPTION

FIG. 1 is a front elevation view of a new, original, and ornamental design of an oral motor chew tool in accordance with my design;

FIG. 2 is a back elevation view thereof;

FIG. 3 is a top front perspective view thereof;

FIG. 4 is a left side elevation view thereof;

FIG. 5 is a right side elevation view thereof;

FIG. 6 is a bottom plan view thereof; and,

FIG. 7 is a top plan view thereof.

The portions inside the areas shown in broken lines form no part of the claimed design.

1 Claim, 5 Drawing Sheets
